TREATMENT OF HYDROCARBON OIL

Charles D. Lowry, Jr., and Felix J. Skowronski,
Chicago, Ill., assignors, by mesne assignments,
to Universal Oil Products Company, Chicago,
Ill., a corporation of Delaware

Application February 29, 1932, Serial No. 595,708

13 Claims. (Cl. 196—50)

This invention relates more particularly to the treatment of lower boiling cracked distillates to increase their anti-knock value.

More specifically the invention has reference to a treatment whereby the percentage of aromatic and unsaturated compounds in cracked gasolines is increased to the greatest possible extent consistent with the production of a motor fuel having high anti-knock characteristics and at the same time free from objectionable properties which sometimes are inherent in hydrocarbon mixtures of this character.

The naphthas or pressure distillates produced by the intensive heat treatment of heavy hydrocarbon oil mixtures such as topped crudes and heavy distillates therefrom contain higher percentages of olefins, naphthenes and aromatics than fractions of corresponding boiling point range produced by the straight run distillation of the same crude petroleums, and the classes of hydrocarbon compounds mentioned add valuable properties to the gasoline fractions on account of their slow burning tendencies as compared with saturated or paraffinic hydrocarbons of similar boiling point. However, it is not practical commercially to increase the content of these constituents above a certain point in ordinary cracking operations on account of the formation on the one hand of increasingly large amounts of gas and highly unsaturated hydrocarbons and on the other hand of heavy polymerized substances typified by tars and coke. By subjecting cracked naphthas or gasolines to re-cracking or reforming operations notable improvements in knock rating can be obtained by suitable control of operating conditions, but again the increase in anti-knock rating may be limited by economic considerations. The present process comprises a combination of operating steps by means of which the percentage of anti-knock compounds in cracked gasolines may be economically increased to a point above that possible by the use of previously known processes.

In one specific embodiment the invention comprises subjecting petroleum naphthas containing substantial amounts of gasoline boiling fractions to the action of liquid sulfur dioxide to separate said naphthas into a fraction of a predominantly aromatic and unsaturated character and a fraction of a predominantly paraffinic character, removing sulfur dioxide from the former fraction and recovering motor fuel fractions of high anti-knock value, subjecting the paraffinic fraction to conversion conditions of temperature and pressure, further subjecting the condensed overhead

low-boiling products from the conversion treatment to separation by means of liquid sulfur dioxide and continuing the operations until a motor fuel of desired anti-knock value is obtained.

In a further specific embodiment the invention comprises cracking hydrocarbon oils to produce overhead gasoline fractions which are cooled, condensed and collected, heavy residual products which are rejected from the system, and intermediate insufficiently converted fractions, separating the intermediate fractions into a fraction of a predominantly aromatic and unsaturated character and a fraction of a predominantly paraffinic character by means of the solvent action of liquid sulphur dioxide, returning the paraffinic fraction to the heating zone of the cracking process for further conversion, removing the sulfur dioxide from the aromatic fraction and recovering the latter.

The attached drawings show diagrammatically in side elevation two forms of apparatus in which the process may be carried out.

Fig. 1 shows an arrangement of apparatus suitable for the treatment of naphthas according to the first specific embodiment given, and

Fig. 2 shows a plant of somewhat more complex design in which heavier oils may be cracked and the naphtha subjected to treatment with liquid sulfur dioxide to produce aromatic fractions for use as motor fuel and paraffinic fractions suitable for further conversion, according to the second specific embodiment given.

Referring to Fig. 1, naphthas containing substantial percentages of gasoline boiling fractions may be introduced to the system through a supply line 1, containing control valve 2, and leading to a feed pump 3 which in turn discharges to a line 4, containing a control valve 5. Line 4 may receive a portion of the end products of the process which are cycled for further treatment from a line 60, as will be later described.

Line 4 joins a line 18 supplying liquid sulfur dioxide in regulated amount, the mixture of oil and solvent passing through a line 6, containing control valve 7, to a mixer 8 which may be supplied with baffling devices to insure thorough contact and obtain maximum solvent action of the liquid sulfur dioxide. The solution of aromatic and unsaturated hydrocarbons in the sulfur dioxide along with the insoluble paraffinic hydrocarbons may be discharged together through a line 9, containing a control valve 10, to a separator 11, still under pressure sufficient to prevent any substantial vaporization of the liquid sulfur dioxide. The actual pressure employed up to

and through the separator will depend upon whether the treatments are conducted at relatively low temperatures obtainable by refrigeration or whether ordinary atmospheric temperatures are employed in which case pressures above the corresponding boiling points of liquid sulfur dioxide will be necessary. The actual choice of temperature and pressure conditions will depend upon a number of factors and the invention comprises the use of any conditions found necessary to efficient operation.

Separator 11 is preferably of a capacity to permit efficient separation of insoluble paraffinic hydrocarbons from the solution of aromatic and unsaturated hydrocarbons in liquid sulfur dioxide. The solution, being of higher specific gravity than the insoluble oils, may be withdrawn from the bottom of the separator through a line 12, containing a control valve 13, to an intermediate receiver 14 in which the pressure is preferably reduced and the temperature raised if necessary until the best conditions are obtained for the substantially complete vaporization of the sulfur dioxide to leave a hydrocarbon residue of a highly aromatic and unsaturated character.

The sulfur dioxide evolved as a gas or vapor may require some purification from hydrocarbon oil vapors prior to their recompression to produce liquid sulfur dioxide for further use and the hydrocarbons separated may also require a limited treatment of some character to remove dissolved sulfur dioxide. However, the general character of such steps is well known and needs no special description at this point, the description being given on the assumption that such steps have been employed though no means for accomplishing them is shown in the drawings for the sake of avoiding undue complexity.

The sulfur dioxide evolved from receiver 14 as a gas is then recompressed and liquefied, being passed through line 15, containing control valve 16, to a suitably designed compressor 17 from which it is pumped as a liquid (after absorption of the heat of compression) through line 18, containing control valve 19, for further use as a solvent in the cycle already described. The disposition of the hydrocarbons separating in receiver 14 will be hereinafter described.

The insoluble paraffinic hydrocarbon oil fraction is indicated as being released from the upper portion of separator 11 through line 20, containing control valve 21, and again it is assumed that suitable steps will be taken for the removal of any dissolved sulfur dioxide prior to the admission of the fractions to the conversion step. Thus, a pump 22 receives the portions of the original naphtha which have the lowest anti-knock value on account of their generally paraffinic character and discharges them through a line 23, containing control valve 24, to line 25, containing control valve 26, and thus to a tubular heating element 27 disposed to receive heat from a furnace 28. Line 25 also receives reflux condensate suitable for further conversion from line 45 as will be presently described.

Temperatures and pressures employed in the heating coil and the reaction chamber following will as a general rule be somewhat higher than those employed when heavier charging oils are cracked owing to the greater volatility and heat stability of the lighter stocks. Thus, temperatures may be employed ranging from approximately 950 to 1100° F. and pressures as high as 500 or 600 pounds per square inch or 75 higher to obtain cracking conditions of sufficient

intensity to insure the desired degree of decomposition. The products from the heating element may be discharged through a line 29, containing a control valve 30, and enter an enlarged zone 31 in which decomposition reactions are allowed to progress to any desired degree without further addition of heat, the reaction chamber 31 being preferably well lagged to reduce radiation heat losses to a practical minimum.

The mixture of conversion products from chamber 31 may be discharged in toto through line 32, containing control valve 33 leading from the bottom of the chamber to a vaporizer 34 which is preferably maintained at a somewhat lower pressure so that the non-vaporized liquids separating at this point may be only those of a tarry or pitchy character unsuited to further conversion treatment, these being preferably withdrawn and rejected from the process through a line 35, containing a control valve 36.

The vapors from vaporizer 34 may be passed to a fractionator by way of vapor line 37, containing control valve 38 and line 39, containing control valve 40 formed by the junction of line 37 with line 40 to be presently described. In fractionator 41 conditions may be so maintained that overhead fractions of substantially gasoline boiling range are evolved along with fixed gases, the mixture being passed through line 41, containing control valve 42, through condenser 43 in which liquefiable constituents of the mixture are condensed and then through line 44, containing control valve 45, to a receiver 52 in which fixed gases are separated from liquids, the former being released at a controlled rate through gas line 46, containing control valve 47 and the latter removed to storage through line 48, containing control valve 49 when they are of proper quality.

Reflux condensates from fractionator 41 of higher boiling range than is desired in finished gasoline from the process will be conducted through a line 42, containing control valve 43, to a recycle pump 44 from whence they are discharged through line 45, containing control valve 46 to the conversion zone as already described.

In the event that the anti-knock value of the liquid in receiver 52 is not as high as desired, a portion or all of the liquid may be reprocessed. Thus, a recirculating pump 59 may take suction on the liquid in receiver 52 through a line 57, containing a control valve 58, and discharge same by way of line 60, containing control valve 61, to line 4 as already described.

The mixture of aromatic and olefinic hydrocarbons separated from the sulfur dioxide solution in receiver 14 may be passed through a line 62, containing a control valve 63, to a pump 64 which discharges the mixture through a line 65, containing control valve 66, through a heating element 67 disposed to receive heat from a furnace 68. Heat is preferably supplied at this point to accomplish at least the vaporization of those compounds of gasoline boiling point range so that the heated liquids discharged into fractionator 41 by way of line 69, control valve 70, and line 39 and control valve 40 may be fractionated into a high anti-knock overhead fraction and reflux condensates which may be further converted to produce more low boiling hydrocarbons, these heavier portions of the sulfur dioxide extracted oils mingling with the other reflux condensates in the fractionator and passing to the heating element through line 42 as already described.

From the above description the completely

cyclic character of the process is evident, the method of operation being such that from a naphtha of any character a high yield of anti-knock value motor fuel may be obtained in a particularly efficient and economical manner.

Referring to Fig. 2, hydrocarbon oils to be treated may be admitted to the system through a feed line 101, containing a control valve 102, and discharged by a pump 103 through a line 104, 10 containing a control valve 105, into and through a heating element 106 disposed to receive heat from a furnace 107, line 104 receiving cycle stocks from lines 103 and 105 as will presently appear.

The oils best suited to treatment in a plant arrangement of this character are the heavy charging oils which are ordinarily charged to commercial cracking processes for the production of gasoline and may comprise heavy uncracked petroleum fractions such as residua or heavy distillates or in some cases cracked residua or intermediate cycle stocks. The temperature and pressure conditions employed will be as a general rule less severe, temperatures ranging from approximately 875 to 935° F. and pressures of from 20 100 to 300 pounds per square inch comprising the usual conditions. The best conditions for any particular charging oil will usually be a matter of trial, the amount of cycling of the various intermediate products of the process having a determining effect.

Products from the heating element may be passed through a transfer line 108, containing a control valve 109, and be admitted to a reaction chamber 110 in which the conversion reactions 35 initiated and partly completed in the heating element may be allowed to progress to any desired point, such a chamber being preferably well insulated to conserve heat units necessary for continuance of the endothermic conversion reactions.

While reaction chamber 110 is shown as one to which the heating element products are admitted to the top and totally discharged through line 111 at the bottom, this feature is not necessarily peculiar to the present process but other types of reaction chambers may be employed or, if advantageous for any purpose, the reaction zone may be entirely omitted. Similarly, the pressure maintained in the reaction zone shown 50 may be substantially the same as that obtaining at the exit of the heating element, or may be reduced.

The products from the reaction chamber, both vaporous and liquid, may be passed through valve 112 in line 111 and enter a chamber 113 under considerably reduced pressure, in the neighborhood of 50 to 100 pounds per square inch, and the heavy residual products not adapted to further heat treatment may be separated therein, 60 being withdrawn through line 114, containing valve 115, if liquid, and subjected to a coking operation in equipment not shown in the drawings, or coke may be produced in the evaporator as desired.

Vapors from the evaporator may be conducted 65 through a line 116, containing a control valve 117, and admitted to a fractionator 118, which is preferably of a design and capacity for producing a plurality of intermediate fractions in addition to overhead gasoline fractions of desired boiling point range. By suitable control of cracking conditions in the preceding unit the vapors passing overhead from the fractionator through line 119 and valve 120 may be of a character corresponding to a high knock rating such as 80

octane number or thereabouts, the control of this property residing somewhat in the possibility of producing fractions of boiling range corresponding to maximum octane number at this point irrespective of yields. The vapors then follow 5 the ordinary course of condensation by condenser 121, the cooled fixed gases and gasoline fractions passing through run-down line 122 and valve 123 to a receiver 124, which is provided with the customary gas release line 125, containing control valve 126, and a liquid draw line 127, containing control valve 128. The liquid fractions thus removed from the primary stage of the process may be reserved for blending with secondary products, as will be later described.

Heavy reflux condensates accumulating in the bottom of fractionator 118 may be either returned to the heating element of the cracking zone for further conversion or passed directly to the liquid sulfur dioxide extraction stage. In either event 20 they may be withdrawn from the fractionator through line 129, containing control valve 130 and pumped by pump 131 first through line 132, containing control valves 133 and 133' and then either to the heating element by way of line 197 25 and valve 198 and line 195 and valve 196 in succession, or may pass to mixer 141 of the treating unit through valve 133', valve 139 and line 140, with valve 198 closed.

When the reflux condensates produced in the 30 bottom of fractionator 118 are too heavy to be advantageously treated with liquid sulfur dioxide, side cuts may be taken from the fractionator through line 134, containing control valve 135, or similar lines, and these fractions pumped by 35 pump 136 through line 137, containing control valve 138, into line 140 and thence to the sulfur dioxide mixer 141. A portion or all of the end product liquids may also be passed to pump 136 from receiver 124 through line 127', containing 40 control valve 128'. In this way there is offered a control of boiling point range of the fractions subjected to the sulfur dioxide treatment. The liquid sulfur dioxide treating plant consists, as shown in the drawings, of a mixer 141 and a separator 149, though a commercial treating plant of this character would necessarily involve a considerably more complex arrangement of apparatus, the simple set-up being shown as sufficient for the present purpose.

Liquid sulfur dioxide, or the gaseous phase of the same, may be admitted to line 142 from some outside storage or from line 158, as will be presently described, and drawn through valve 143 by a compressor 144. In case gaseous SO₂ is fed 55 to the compressor it must have sufficient capacity to liquefy the gas and discharge the same through line 145, containing control valve 146, leading to the mixer. In this case also, cooling means may need to be interposed in line 145 to absorb the 60 heat of compression, though these means are not indicated in the drawings.

The proportions of liquid sulfur dioxide employed in respect to the amount of oil admitted in the mixer will depend upon the character of 65 the hydrocarbon mixtures admitted in regard to their content of aromatic, naphthenic and olefinic constituents and the temperature and pressure conditions chosen for the treating operation. When the oils treated have a low solidifying point they may be treated at relatively low temperatures so that the pressure upon the mixer and the succeeding separator is relatively low, whereas if ordinary or superatmospheric temperatures are maintained, correspondingly in- 70 75

creased pressures must be employed to maintain the sulfur dioxide in a liquid state. Mixer 141 may contain any type of filling or baffling material necessary for providing a tortuous path of flow and insure thorough contact of the oils with the solvent.

The mixer products comprising a solution of hydrocarbons of a predominantly aromatic and olefinic character in the liquid sulfur dioxide, and the insoluble liquids of a more distinctly paraffinic nature may then be passed through line 147, containing control valve 148, into separator 149, in which substantially the same pressure is maintained which has been found to be necessary to prevent vaporization of the sulfur dioxide. In this separator the solution of oil in liquid sulfur dioxide will gradually settle to the bottom while undissolved fractions will rise to the top on account of differences in specific gravity. Separator 149 is again shown to represent any type of separating apparatus and will usually be more complex than the simple tank shown.

At this point one of the important features of this invention is again to be noted, that is, that the more highly paraffinic fraction is returned directly to the heating zone of the cracking process for further conversion while the sulfur dioxide-soluble hydrocarbons are separately treated to produce high knock rating blending fluid and reflux condensates which are separately returned to the cracking process. Thus, intermediates from the cracking process containing components of lowest knock rating are continually re-subjected to conversion conditions to produce increased yields of anti-knock fractions, these SO_2 -insoluble mixtures being taken through line 150, containing control valve 151 and discharged by pump 152 through line 153, containing control valve 154, to combined feed line 104. These fractions, which usually contain a certain amount of dissolved sulfur dioxide may be subjected to moderate heat treatment or alkaline washing, or both, to remove the traces of sulfur dioxide prior to the re-admission of the oils to the cracking zone, though means for effecting this object have been omitted from the present drawings for purposes of simplification.

The solution of aromatics, olefins, etcetera, in liquid sulfur dioxide is removed from the bottom 50 of the separator through a line 155, containing a control valve 156, and passed to low pressure separator 157, wherefrom the liquid sulfur dioxide is vaporized and returned through line 158, containing control valve 159, to the suction side of 55 compressor 144, as already indicated. Again, with the object of avoiding unnecessary detail, separator 157 has been shown without any means for exterior heating to effect the complete removal of sulfur dioxide from the hydrocarbon oils, 60 though such means usually have to be employed for this purpose. Furthermore, it may be necessary to condense out volatile hydrocarbons from the sulfur dioxide prior to its re-compression and liquefaction, and for a similar reason such equipment has been omitted from the drawings.

The sulfur dioxide-soluble fraction is taken 65 from separator 157 by a pump 162 through line 160 containing a control valve 161, and discharged through line 163, containing control valve 164, into and through a heating element 165 suitably disposed in furnace 166. During 70 passage through the heating coil, sufficient heat is added to vaporize all or a suitable portion of the extracted oils so that they may be subjected to vapor phase treatment to fit them for

material suitable for blending with the lower boiling gasoline fractions from the first stage of the process. While the operation being described is limited to a particular type of vapor phase treatment, other vapor phase treatments may be used or the extracted liquids may be refined in liquid phase by sulfuric acid and other reagents and re-vaporized. However, the vapor phase treatment to be presently described is particularly adapted to the treatment found to be necessary in suitably refining these oils and it will be given in essential detail.

Heated and vaporized oils may be passed from the tubular heating element through a transfer line 167, containing a control valve 168, and admitted to lower vapor space 174 of vapor phase treater 171 after the addition of regulated amounts of hydrochloric acid either in solution or as a wet gas from line 169, containing control valve 170. Vapor phase treater 171 contains solid contact material of a metallic or adsorbent character in space 172, this material being supported upon a perforated false bottom 173. While the present description is confined to an up-flow treatment with some accompanying fractionation, down-flow treatments may also be employed, in which case a greater burden is placed upon the succeeding fractionator.

Hydrochloric acid and solid contact materials, particularly those of a metallic character, such as, for example, granulated zinc, copper or brass are effective for the more or less selective polymerization of highly unsaturated gum-forming hydrocarbons undesirable in a finished gasoline for obvious reasons. Some desulfurization may also be effected, depending upon the proportion of electro-negative metals, such as copper, in the contact mass, either in mechanical admixture or alloyed with electro-positive metals. Heavy polymers and reaction products accumulating in lower section 174 of the vapor phase treater may be removed therefrom through a draw line 176, containing control valve 177 and disposed of in the most advantageous manner. For example, the hydrocarbons may be separated from any sludge reaction products and returned to the cracking unit and the sludge materials, comprising at times heavy metal chlorides, may be either wasted or returned to the contact mass after suitable purification.

Treated vapors accumulating in upper section 175 of the vapor phase treater may be conducted to a final fractionator 180 through a line 178, containing a control valve 179, and subjected to fractionation to produce refined overhead fractions to be blended with the overhead fractions from the cracking unit. Owing to the highly aromatic character of these secondary overhead fractions, as evidenced by their octane number, which is frequently as high as 100-120, they constitute a valuable product of the process and are preferably blended with the primary cracked overhead fractions to produce a composite motor fuel of exceptionally high knock rating. Such vapors may be passed from the fractionator through a line 181, containing a control valve 182, and condensed during passage through a condenser 183, the liquid fractions being passed through run-down line 184, containing control valve 185, to receiver and separator 186, from which fixed gases may be released through a line 187, containing a control valve 188, and the liquids withdrawn through a line 189, containing a control valve 190, either for direct blending with the primary cracking plant fractions or in-

termidate storage. The blending may be effected by passing cracked distillate from receiver 124 into line 181 through line 181', having valve 182'.

5 The reflux condensates from fractionator 180, constituting relatively heavy oils though still of a highly aromatic character, may be either cycled to the heating zone of the cracking plant or to the sulfur dioxide treating plant. These 10 fractions are withdrawn from the fractionator through a line 191, containing a control valve 192, and pumped by pump 193 through line 194, containing control valve 195', to the junction of lines 195 and 197, the former leading to combined feed line 104 of cracking plant and the latter to line 132 leading ultimately to mixer 141. The preferred disposal of these heavy fractions will be determined experimentally in most cases.

20 The foregoing plant hook-ups used in describing characteristic operations are capable of many modifications and, owing to the wide variety of charging stocks which can be cracked and treated in plants of this general character, specific examples of results obtainable could be multiplied considerably. Two, however, will be sufficient to show the merits and advantages of the process and cases will be taken involving the processing of (1) a naphtha produced from Pennsylvania 25 crude oil, and (2) a heavy gas oil fraction produced in the primary distillation of a mixture of Mid-Continent and West Texas crude oils. The results obtainable in the first case may be by the operation of a plant of design generally similar 30 to that shown in Fig. 1 and in the second case from a hook-up similar to Fig. 2.

The naphtha in the first case may contain approximately 85% of hydrocarbons boiling under 400° F., the raw gasoline produced by simple fractionation having the properties shown in column 40 1 while the corresponding properties of a gasoline produced by the application of the process has the properties shown in column 2.

Comparison of gasolines

	1	2
Gravity °A. P. I.	60	55
End point °F.	400	390
Octane number	45	75

55 The yield of gasoline from the naphtha may be reduced from approximately 85% to 83% by this treatment which is more than compensated for by the marked increase in anti-knock value.

The general properties of the charging oil which may be processed in a manner generally similar to that described in connection with Fig. 2 are indicated by its gravity of 30° A. P. I. and its content of 5% of hydrocarbons boiling below 437° F. and 25% below 572° F. By the most economic cracking of this stock in a cracking unit generally similar in character to the primary unit shown in the drawings it is possible to produce a yield of 60% of gasoline having a final boiling point of 390-400° F. and an octane number of 65, with the concurrent production of 25% of 6° A. P. I. gravity fuel oil residuum and 15% by weight of fixed 65 gases.

70 By combining a cracking unit with a sulfur dioxide treating unit and a vapor phase treater as described, the yield of gasoline overall may be increased to 78%, the residuum decreased to 13% and the gas loss to 9%, the gasoline having the

same endpoint and substantially the same distillation curve, but an octane number of 90.

In operating to produce the improved yields and quality in the gasoline, 60% of 325° F. endpoint overhead stock may be condensed from the cracking plant fractionator, while 25% of a mixture of side cuts and bottom refluxes on a basis of the oil charged may be treated in the sulfur dioxide treating unit. Using two volumes of liquid sulfur dioxide to one of oil in the treating plant under suitable conditions of temperature and pressure may cause an approximately equal split of these oils into paraffinic cycle stock returned to the heating element for further cracking and a mixture of aromatic hydrocarbons which, after 15 refining by the vapor phase treatment indicated, may have the following properties:

Gravity °A. P. I.	37
I. B. P.	322° F.
20% over at	20
50% over at	337° F.
90% over at	345° F.
Endpoint	366° F.
Sulfur	400° F.
0.05%	25
Saybolt color	27
Doctor test	OK
Copper strip test	OK
Octane number	100

The tabulated properties of the secondary or 30 aromatic blending stock permit, therefore, its blending with the primary overhead gasoline to produce a finished gasoline having a knock rating of 90 octane number. For purposes of better 35 comparison, the comparative data on the two types of operation are tabulated below, column 1 showing figures corresponding to ordinary cracking operation, and column 2 figures corresponding to the improved process of the present invention:

Gasoline yield %	60	78
Octane number	65	90
Residuum, yield %	25	13
Gas, yield %	15	9

40 In operations of the general character under discussion the overall recycle ratio, including primary and secondary refluxes and sulfur dioxide-insoluble oils, may be considerably lower 50 than in straight cracking operations, since the portions of the charging stock requiring more intensive decomposition are cracked selectively.

The foregoing specification, including the description of two operations and results obtainable therefrom, will be sufficient for accurately defining the nature and scope of the invention, but since other modifications are possible with corresponding variations of results none of the preceding specification is to be construed as imposing undue limitations upon the broad scope of the invention.

We claim as our invention:

1. A continuous process for converting a cracking stock into high octane number gasoline, 65 comprising the steps of cracking the stock to form a cracked gasoline, separating the latter into a low boiling fraction and a high boiling fraction, treating the high boiling fraction with liquid SO_2 , separating the raffinate and extract, 70 removing the solvent therefrom, recycling the raffinate by mixing it with the cracking stock entering the cycle, and blending said extract with said low boiling fraction to produce the high octane number gasoline. 75

2. A process for the manufacture of high octane number gasoline comprising mixing the liquid- SO_2 insoluble hydrocarbons from the high boiling portion of a cracked gasoline with cracking stock containing both saturated and unsaturated hydrocarbons, cracking the mixture to form a cracked gasoline, dividing the latter into a low boiling fraction and a high boiling fraction, treating the high boiling fraction with liquid- SO_2 separating out the extract, removing the solvent therefrom, and blending said extract with said low boiling fraction.

3. A process for converting substantially the entirety of an ordinary cracking stock, containing both saturated and unsaturated hydrocarbons, into a high octane number gasoline, comprising cracking said stock to form a cracked gasoline, dividing the latter into a low boiling fraction and a high boiling fraction, treating the high boiling fraction with liquid- SO_2 , separating the raffinate and extract, removing the solvent therefrom, blending said extract with said low boiling fraction to form a high octane number gasoline, mixing said raffinate with cracking stock containing both saturated and unsaturated hydrocarbons, cracking the mixture so as to form a cracked gasoline, subjecting the cracked gasoline to the appropriate sequence of process steps described above, and in like manner treating the successive raffinate resulting from continuing the process herein set forth.

4. A process for converting substantially the entirety of a cracked gasoline into a high octane number gasoline, comprising dividing the cracked gasoline into a low boiling fraction and a high boiling fraction, treating the high boiling fraction with liquid- SO_2 , separating the raffinate and extract, removing the solvent therefrom, blending said extract with said low boiling fraction to form a high octane number gasoline, mixing said raffinate with cracking stock containing both saturated and unsaturated hydrocarbons, cracking the mixture so as to form a cracked gasoline, subjecting the latter to the foregoing sequence of steps described for the cracked gasoline, and in like manner treating the successive raffinate resulting from continuing the process herein set forth.

5. A process for the production of a highly olefinic anti-knock motor fuel comprising cracking a hydrocarbon charging stock, separating a light cracked naphtha and a heavy cracked naphtha, contacting said heavy cracked naphtha with a selective solvent, separating a raffinate fraction and an extract fraction, removing solvent from each of said fractions, recycling at least a portion of the raffinate to the cracking step and blending at least a portion of said light cracked naphtha and at least a portion of said extract.

6. A process for the production of anti-knock motor fuel which comprises subjecting a hydrocarbon oil to cracking conditions of temperature and pressure, separating a light cracked naphtha and a heavy cracked naphtha, contacting said heavy cracked naphtha with a selective solvent to form a paraffinic fraction and an unsaturated fraction, removing solvent from each of said fractions, recycling at least a portion of the paraffinic fraction to the cracking step, and blending at least a portion of said light cracked naphtha

and at least a portion of said unsaturated fraction.

7. The process as defined in claim 6 further characterized in that said hydrocarbon oil comprises an oil heavier than gasoline in addition to said portion of the paraffinic fraction recycled to the cracking step.

8. A process for producing anti-knock motor fuel from low boiling distillates of the character of gasoline and naphtha, which comprises treating the distillate with liquid- SO_2 or like solvent separating the resultant raffinate and extract and removing solvent therefrom, combining the raffinate with a cracking stock, cracking the resultant mixture and blending gasoline boiling hydrocarbons thus formed with gasoline boiling portions of said extract.

9. The process as defined in claim 8 further characterized in that said cracking stock is a hydrocarbon oil heavier than said distillate.

10. A process for producing anti-knock motor fuel which comprises cracking a paraffinic oil formed as hereinabove set forth, separating the resultant cracked gasoline into a low boiling fraction and a high boiling fraction, treating the latter with liquid- SO_2 or like solvent, separating the resultant raffinate and extract and removing solvent therefrom, supplying the raffinate to the cracking step as said paraffinic oil, and blending said low boiling fraction with gasoline boiling portions of said extract.

11. A process for producing anti-knock motor fuel which comprises cracking a hydrocarbon oil heavier than gasoline, separating the resultant cracked gasoline into a low boiling fraction and a high boiling fraction, treating the latter with liquid- SO_2 or like solvent, separating the resultant raffinate and extract and removing solvent therefrom, recycling the raffinate to the cracking step for further cracking in admixture with said hydrocarbon oil, and blending said low boiling fraction with gasoline boiling portions of said extract.

12. A process for producing anti-knock motor fuel from a petroleum cracking stock which comprises cracking the stock, separating the resultant cracked gasoline into a low boiling fraction and a high boiling fraction, treating the latter with liquid- SO_2 or like solvent, separating the resultant raffinate and extract and removing solvent therefrom, recycling the raffinate to the cracking step for further cracking in admixture with said stock, and blending said low boiling fraction with gasoline boiling portions of said extract.

13. A process for producing anti-knock motor fuel from low boiling distillates of the character of gasoline and naphtha, which comprises treating the distillate with liquid- SO_2 or like solvent, separating the resultant raffinate and extract and removing solvent therefrom, cracking the raffinate and fractionating resultant cracked vapors in a fractionating zone, introducing the extract to the fractionating zone for fractionation therein together with said cracked vapors, recycling reflux condensate from the fractionating zone to the cracking step for further cracking in admixture with the raffinate, and finally condensing the gasoline vapors uncondensed in the fractionating zone.
